UNITED STATES PATENT OFFICE.

GEORGE S. BARKENTIN, OF NEW BRITAIN, CONNECTICUT, ASSIGNOR TO P.
& F. CORBIN, OF SAME PLACE.

DESIGN FOR ORNAMENTAL PANELS ON ARTICLES OF BUILDERS' HARDWARE.

SPECIFICATION forming part of Design No. 13,568, dated February 8, 1883.

Application filed November 9, 1882. Term of patent 7 years.

To all whom it may concern:

Be it known that I, GEORGE S. BARKENTIN, a citizen of the United States, residing at New Britain, in the county of Hartford and State of Connecticut, have invented and produced a new and original Design for Ornamental Panels on Articles of Builders' Hardware, of which the following is a specification, reference being had to the accompanying drawing, forming part 1c thereof.

The drawing shows a front elevation of my design as applied to the leaf of a butt-hinge.

In practice I intend to apply the leading features of this design, hereinafter specified, 15 to a full line of builders' hardware, including the face-plate or front for the latch and lock, the key-hole and knob escutcheons, the knob, and other articles.

The leading feature of my design consists of 20 the ornamentation of the groundwork or sunken surface of the panels by a series of conventional flowers having diamond-shaped outlines and nearly touching each other, the space or division between the flowers dividing the surface of the panel into diamond shaped figures, as shown. I have herein illustrated these flowers as composed, first, of a small sunken center of circular form; second, sunken lines or depressions radiating therefrom to represent 25 the surface and veins of the flower-petals; third, four short depressions to divide the flower into four petals; and, fourth, a diamond-shaped 30

groove or depression which incloses each flower. These grooves and flowers are so placed that the grooves are continuous, and cross each other obliquely in two series of parallel lines, and with the flowers in the diamond - shaped space inclosed thereby. In all cases, whether the design is applied to a hinge or other articles of builders' hardware, I intend to make the 35 40 design by depressions and elevations in the surface of the metal—as, for instance, by casting, engraving, or stamping—and to inclose the same by a raised border to form a panel, the contour of which panel may be round, rectangular, or other desired form.

Instead of radial lines or depressions in the petals of the flower, each petal may be ornamented by a single concave depression to represent the face of the petal, leaving the other 45 50 features of the design as hereinbefore described, and it will present the same general appearance.

I claim as my invention—

The design for the ornamental panels on articles of builders' hardware herein shown and described, the same consisting of a series of diamond-shaped conventional flowers separated by lines on the groundwork of the panel. 55

GEORGE S. BARKENTIN.
